UNITED STATES PATENT OFFICE.

ELMER H. SMITH, OF MINNEAPOLIS, MINNESOTA.

CONTROLLING MEANS FOR CARBIDE FEEDERS.

Application filed October 2, 1922. Serial No. 591,995.

The object of my invention is to provide means for automatically controlling the feed of carbide to an acetylene generator to the end that the mechanism will be automatically checked when pressure of the gas reaches a predetermined point, and resumed when the pressure falls below a predetermined point.

The invention consists generally in various constructions and combinations all as hereinafter described and pointed out in the claims.

In the accompanying drawings forming part of this specification,

15 Figure 1 is a vertical sectional view through a motor embodying my invention:

Figure 2 is a sectional view on the line 2—2 of Figure 1.

20 Figure 3 is a sectional view on the line 3—3 of Figure 1.

Figure 4 is a detail sectional view showing the motor control mechanism.

25 Figure 5 is a view showing a carbide generator and its connection with a port opening into the Bourdon tubes for supplying gas from the generator to the tubes.

30 In the drawing, 2 represents the frame of the motor having an operating spring 3 mounted therein, and a train of gears 4; the main gear has a shaft 5 provided with a blade or sweep 6 which operates to deliver the carbide from the feed table to the generating tank. These devices, however, form no part of my present invention and I do 35 not illustrate them herein.

35 7 represents a centrifugal governor shaft having governors 8 thereon and connected with the train of gears to be operated thereby. On the governor shaft, a disc 9 is secured to revolve therewith and evidently whenever this disc is checked against revolution, the governor shaft and governors will also be stopped, and with them the train of gears from which the feed disc or sweep is 40 operated.

45 A rod 10 is mounted to slide in guides 11 and 12 in the motor frame and normally held in its depressed position by a spring 13, and a Bourdon tube 14 is mounted in the frame of the motor and connected at one end with the rod 10; the opposite end of the tube having a port 15 for communication with the gas supply in the generator. A friction disc 16 is mounted on the rod 10 having a suitable surface 17 for engagement with the disc secured to the governor shaft, and when

the pressure of the gas rises above a predetermined point, say 10 pounds, the Bourdon tube will be partially straightened, raising the rod 10 and moving the friction disc into engagement with the disc 9, and checking the movement of the train of gears and the feed of the carbide. As soon as the pressure falls, the spring 13 will disengage the friction disc and allow the movement of the motor to be resumed.

I prefer also to provide a rod 18 mounted to slide in guides in the motor frame and connected with the second Bourdon tube 19 and having a pair of friction discs 20 and 21; one above, and the other below the disc 9 on the governor shaft. A spring 22 is provided on this rod 18, for normally holding the upper friction disc 20 on the governor disc and preventing operation of the train

45 of gears and the motor when there is a low supply of gas in the generator, as for instance, when the cover is removed, and it is desired to do some work around the generator without allowing the motor to run

50 down, or when the carbide supply for any reason is exhausted. When the supply is renewed, and the cover replaced and it is desired to start the machine, then the attendant can raise the rod 18 by the pressure of the finger, releasing the train of gears

55 and allowing the motor to feed carbide until the pressure rises above a certain point, say for instance 3 pounds. At that time, the Bourdon tube 19 will hold the friction disc 90 out of engagement with the governor disc

60 and allow the feed of the carbide to be continued until it is automatically checked either by the friction disc 16, or by the friction disc 21 which is arranged preferably at

65 a lower level than the disc 16, and is only intended for operation or use in case of failure of the disc 16 to perform its functions and when the pressure of gas in the generator rises above a certain degree, say for instance, 15 pounds. At that point the disc 21

70 will engage the governor disc, being raised by the movement of the Bourdon tube 19, and thereupon operation of the motor and feed of the carbide will be checked, until the pressure falls to a predetermined degree.

I prefer also to provide a disc 32 on the governor shaft in position for being engaged by a friction disc 23 mounted on a screw 24 in the frame in the motor; said screw having a finger grip 25 and adapted to be revolved manually to engage the disc 23 with the disc

32 or separate them as desired. This disc 23 serves as a speed governor and the user may raise and lower it to and from the disc 32 and thereby control the speed of the machine.

As shown in Figure 5 gas from the generating chamber 35 will pass through the conduit 36 to the port 15 for delivering gas to the Bourdon tubes. The generator will 10 have as usual a carbide hopper from which the carbide is supplied to the chamber and spread by the distributor or sweep 6.

I claim as my invention:

1. An automatic pressure controlled carbide feed for acetylene generators, comprising a motor, a gas generating chamber, carbide feeding means actuated from the motor; a governor operatively connected with and driven from said motor, and a 20 Bourdon tube cooperatively associated with said governor and formed with a port to receive gas from the generating chamber to actuate said tube to check the motor and carbide feeding means.

2. An automatic pressure controlled carbide feed for acetylene generators, comprising a motor, a gas generating chamber, carbide feeding means actuated from the motor; a centrifugal governor shaft 30 operatively connected with the motor, a disc secured to said shaft, a brake in operative relation to said disc, and a Bourdon tube cooperatively associated with said brake and formed with a port to receive gas from the 35 generating chamber to actuate said tube to apply the brake to the governor disc to check the motor and carbide feeding means.

3. An automatic pressure controlled carbide feed for acetylene generators, comprising a motor, a gas generating chamber, a carbide feeding means actuated from the motor; a centrifugal governor shaft operatively connected with the motor, a disc secured to said shaft, a plurality of Bourdon 40 tubes, each formed with a port to receive gas from the generating chamber, one tube having means for normally engaging said disc to check its movement until the gas pressure in the tube reaches a predetermined 45 degree, and the other tube having means for engaging said disc when the gas pressure rises above a predetermined degree.

4. An automatic pressure controlled carbide feed for acetylene generators, comprising a motor, a gas generating chamber, carbide feeding means actuated from the motor; a governor shaft provided with a friction disc, a plurality of Bourdon tubes, each formed with a port to receive gas from the generating chamber, one tube having 55 means for engaging said disc and normally

holding it until a predetermined pressure is reached in the tube, the other tube having means for engaging the disc when a predetermined pressure is reached in it, and 60 said first named tube having means for engaging the disc and checking its revolution in the event that the checking means of the second-named tube fails to operate.

5. In an automatic pressure controlled carbide feed for acetylene generators, a motor, a gas generating chamber, carbide feeding means actuated from the motor; a Bourdon tube formed with a port to receive gas from the generating chamber, and mechanism 70 operatively connected with said tube and the feeding means and controlled by the movement of said tube through the pressure of the gas therein for checking the operation of the feeding means.

6. In an automatic pressure controlled carbide feed for acetylene generators, a motor, a gas generating chamber, carbide feeding means actuated from the motor; a Bourdon tube formed with a port to receive gas from the generating chamber, a centrifugal governor cooperatively associated with the motor and actuated therefrom, and friction mechanism operable by movement of said tube effected by pressure of gas in the tube 80 for checking the governor and motor.

7. In an automatic pressure controlled carbide feed for acetylene generators, a motor, a gas generating chamber, carbide feeding means actuated from the motor, a centrifugal governor geared to the motor, a plurality of Bourdon tubes each formed with a port to receive gas from the generating chamber, mechanism controlled by one of the tubes through pressure of gas therein for normally 90 checking the feed until the gas reaches a predetermined pressure, and mechanism associated with the tubes and operating successively to check the feed when the gas in the tubes exceeds a predetermined pressure.

8. In an automatic pressure controlled carbide feed for acetylene generators, a motor, a gas generating chamber, carbide feeding means actuated from the motor, a centrifugal governor having a disc connected therewith, a Bourdon tube formed with a port to receive gas from the generating chamber and operative to control the movement of said disc to check or release the feeding means, and a friction device operatively positioned in relation to the governor to check the governor when it exceeds a predetermined speed.

In witness whereof, I have hereunto set my hand this 25th day of September, 1922.

ELMER H. SMITH.
